UNITED STATES PATENT OFFICE

HANS J. ANDRESEN, OF CHICAGO, ILLINOIS

DESIGN FOR A KALEIDOSCOPE

Application filed May 2, 1933. Serial No. 47,965. Term of patent 7 years.

To all whom it may concern:

Be it known that I, HANS J. ANDRESEN, a citizen of the United States, residing in Chicago, in the county of Cook and State of Illinois, have invented a new, original, and ornamental Design for a Kaleidoscope, of which the following is a specification, reference being had to the accompanying drawing, forming a part thereof, in which,

Figure 1 is a perspective view looking toward the front of the kaleidoscope, and

Figure 2 is a perspective view looking toward the rear thereof.

I claim:

The ornamental design for a kaleidoscope, as shown.

HANS J. ANDRESEN.
